(57) **CLAIM**

The ornamental design for a fluid concentrator, as shown.

DESCRIPTION

FIG. 1 is a perspective view of a fluid concentrator showing our new design.

FIG. 2 is a front elevation view of the fluid concentrator of FIG. 1.

FIG. 3 is a back elevation view of the fluid concentrator of FIG. 1.

FIG. 4 is a left elevation view of the fluid concentrator of FIG. 1.

FIG. 5 is a right elevation view of the fluid concentrator of FIG. 1.

FIG. 6 is a top plan view of the fluid concentrator of FIG. 1; and,

FIG. 7 is a bottom plan view of the fluid concentrator of FIG. 1.

The broken lines depict portions of the fluid concentrator that form no part of the claimed design.
